UNITED STATES PATENT OFFICE

JOHN FIELD, OF FAIRFIELD, CONNECTICUT, ASSIGNOR TO THE WARNER BROTHERS COMPANY, OF BRIDGEPORT, CONNECTICUT, A CORPORATION OF CONNECTICUT

CORSET

Application filed July 18, 1932. Serial No. 623,093.

This invention relates to corsets, girdles and the like, and its principal object resides in the provision of an improved garment of this character including portions capable of stretching both up and down and across the wearer and other portions capable of stretching up and down but not across, for purposes hereinafter indicated. Another feature resides in novel provisions for bones in such garments.

Other objects and advantages will become apparent from the following detailed description of certain preferred embodiments of the invention, reference being had to the accompanying drawings wherein:

Figure 1 is a front elevation of one form of garment in accordance with the invention.

Figure 2 is a rear elevation of the garment shown in Figure 1.

Figures 3 and 4 are enlarged sections taken on the lines 3-3 and 4-4 of Figures 1 and 2 respectively.

Figure 5 is a front elevation of a modified type of garment also in accordance with the invention.

Figure 6 is an elevation similar to Figure 5 but showing the front portion of the corset partly broken away.

Figure 7 is a rear view of the form shown in Figures 5 and 6.

Figure 8 is an enlarged section taken on the lines 8-8 of Figure 6.

Figure 9 is a front view of still another embodiment of the invention.

Figure 10 is a view similar to Figure 9 but showing the front portion of the garment partly broken away.

Figure 11 is a rear elevation of the garment shown in Figures 9 and 10.

Figure 12 is a view similar to Figure 11 but showing the rear portion of the garment partly broken away.

Figures 13 and 14 are enlarged sections taken on the line 13-13 and 14-14 of Figures 10 and 12, respectively.

Referring first to the embodiment shown in Figures 1-4, there is illustrated a garment including a plurality of panels 1 of material capable of stretching not only across the body of the wearer but also up and down.

This material is preferably composed of elastic yarn in combination with non-elastic yarn or stop threads adapted to limit the stretch in at least one direction, advantageously across the body, or this material may be made substantially entirely of elastic yarn, that is, without such stop threads. The material may advantageously be of woven character, that is to say, of material having both elastic warp and elastic weft strands, or being flat knit, though for some purposes the material may be of knitted character. Each of these panels preferably extends from top to bottom of the garment, and the up and down extent of the garment is advantageously such that the lower edge 2 thereof lies below the hips and adjacent posterior portions of the wearer.

In the construction illustrated, a plurality of panels of the character mentioned may be employed for lying at either side of the wearer, one panel at each side extending around to the front of the wearer and one around to the rear, although the panels at either side might be replaced by a single panel. These panels may extend at the front and back of the garment, when folded flat, as shown, so that they constitute some portion of the material from one hip bone to the other at both the front and back of the wearer, or if desired only at the back.

At the central front portion of the garment there is employed in the form shown in Figures 1-4 one or more panels 3 of material including elastic yarn so arranged that the material is capable of stretching in an up and down or generally vertical direction but not in a cross-wise or generally horizontal direction. This material is also preferably of woven character. The adjacent edges of the several panels may abut and be joined by stitching 4 as best shown in Figure 3, the stitching desirably being of zig-zag character to permit the required stretching along the seams. However, lap joints and other types of stitching might be substituted. The seams may be covered by elastic stripping 5 sewed to the panel as at 6. Between the stripping 5 and the panel 3 there are preferably provided at the upper, front portion of the garment 100

suitable bones 7, which may be formed of light, flexible, flat metal strips, the stripping serving as pockets in which the bones float. The bones preferably lie lengthwise in the direction in which the material stretches. Where two bones are side by side and covered by single piece of stripping 5, the middle of the latter is preferably stitched to one or more panels as at 8. One or more additional bones may be secured between the edges of panel 3 by stripping 5 where desired. While bones as shown terminate considerably above the lower edge 2 of the garment, they may extend further down where desired. The pockets may be completed at their lower ends by stitching 9 and at their upper ends by stitching 10 which secures elastic binding 11 to the upper edges of the garment. The lower edge of the garment may be similarly finished 20 with an elastic binding 12, and garter attachments 13 secured thereto.

At the rear of the garment a panel 14 may be interposed between panels 1 and secured thereto similarly to the manner already described. The panel 14 is preferably of material like that of which panel 3 is composed, that is to say, of material which stretches up and down but not across, and advantageously extends from top to bottom of the garment. 30 Bones 15 may be retained in pockets formed by stripping 5 and may extend substantially the full length of the garment in unstretched condition. These bones also preferably float in their respective pockets.

35 It may be noted that the garment thus constructed is capable of stretching up and down at all points in its girth, and of stretching across or horizontally at some points, as is particularly advantageous.

40 Through this construction provision is made for confining or flattening action at the front or back of the garment or both and at the same time riding up of the garment upon the figure, particularly caused by bending at 45 the hips, is avoided. Moreover, the bones give additional flattening action without producing folds or wrinkles. The bones may be incorporated into the garment in simple fashion and require no fastening devices. When 50 they are free to float in their pockets as described, or possibly secured at only one end, they do not interfere with the stretching of the material. Through the construction at the front, the bones 7 have the desired effect 55 over the diaphragm without extending over the abdomen with likelihood of discomfort.

60 It will be understood that the front may be constructed as described while the rear is entirely of material such as is employed in panels 1 or vice versa, without sacrificing the advantages at the other points in the garment.

65 At the upper portion of the garment, at one side, provision is made as at 16 for permitting the wearer to step into the same.

65 For instance, hooks and eyes may be em-

ployed, as shown, or a lacing or slide fastener. In this case the lower portion of the girth of the garment is continuous, though the opening may be of any suitable length and even extend clear to the bottom of the garment.

Turning now to Figures 5-8, there is shown a construction which is similar to that described, except that the rear portion 20 of the garment is formed of a unitary panel of two-way stretch material extending across the back of the wearer from one side of the hips to the other and thus constituting about half the girth of the garment. In order to produce the flattening effect described a panel 21 of material capable of stretching up and down but not across may be stitched along its edges to the panel 20. Preferably the panel 21 extends from top to bottom of the garment and is stitched as at 22 along the entire length at either edge, and also at either end to the binding 11 and 12. However, the stitching of the ends of the panel 21 is not essential for accomplishing the main purpose described.

Preferably the capacity of panel 21 to stretch in the up and down direction should be at least as great as that of the panel 20, though the former may be made of relatively fine elastic or otherwise arranged so that the force required to stretch it is less than that which stretches the latter an equal amount. On the other hand the panel 21 should preferably be practically non-stretchable or non-elastic in a transverse or horizontal direction.

In Figures 9-14, the rear portion of the garment is shown constructed as described in connection with Figures 5-8, and the front panel 30 of the garment is shown similarly formed of material which is elastic both up and down and across. In conjunction with this panel 30 there is provided a diaphragm restraining panel 31 formed of material capable of stretching up and down but not across and terminating above the portion of panel 30 which overlies the abdomen. In this manner the confining action at desired points may be achieved, that is, at the upper part of the front of the corset without the need for double thickness of material at other points. The panel 31 preferably terminates about half way down the garment and is free at its lower edge, at which a binding 32 may be applied, and stitched as at 33 along both sides to panel 30. The top of this panel 31 may be sewed to binding 11 and be provided with bones 7 in pockets formed by stripping 5 as described in connection with Figures 1-4. By leaving the lower edge of panel 31 free the stretching of the panel 30 is not interfered with in any way. However, the lower edge of this panel might be secured to the panel 30 or a portion of the latter might be cut away and replaced by an insert of the character of panel 31.

While a particular arrangement and num-

ber of panels has been shown and described in the several embodiments, it will be understood that any single panel might be replaced by a plurality of panels stitched together, or on the other hand, a single panel might be substituted for a plurality of panels shown. Furthermore, the panels might be of larger or smaller size, the panels 1, for instance, extending to a greater or less extent 10 in a transverse direction or direction around the body. It will also be appreciated that, where desired, panels of non-elastic material, or in other words, panels which do not stretch in either direction, may be substituted for 15 other material in the garment. For instance, the whole front of the garment might be made of non-elastic material, while the rear portion might be constructed as described.

Whether the insert or lining form illustrated 20 is employed, the material of the insert or lining, wherever located in the garment, may extend the full length of the same or be of any suitable shorter length.

While the invention has been described in 25 connection with separate panels secured or engaged to one another, the invention comprehends the interweaving of two types of material to secure the same result. That is to say, by a suitable substitution of one type of 30 yarn or thread for another, at convenient points in the manufacturing operations, it is possible to provide a really integral construction having the characteristics of the invention. Accordingly, when the terms "secured" 35 or "engaged" are employed in the specification and claims they are intended as including this form of the invention.

The arrangement and number of the bones 40 may also be varied, or the bones may be omitted where desired. The stripping which cooperates with the bones may be secured only at its ends or along portions of its sides, where desired, instead of securing the stripping along its entire length to the material.

45 Matter shown or described, but not claimed herein, is claimed in my pending application Serial No. 587,869, filed January 21, 1932, and also in my application Serial No. 660,373, filed March 11, 1933.

50

The terms and expressions which have been employed are used as terms of description and not of limitation, and there is no intention, in the use of such terms and expressions, of excluding any equivalents of the features shown and described, or portions thereof, but it is recognized that various modifications are possible within the scope of the invention claimed.

What I claim is:

1. A garment of the character described 75 including a plurality of panels of material formed of elastic yarn and capable of stretching both up and down and across, and a panel of material adapted to stretch up and down but not across secured at the front of said garment, said last-named panel being of less up and down extent than the length of the garment.

2. A garment as claimed in claim 1, where- 80 in the last-named panel is secured along its vertical edges to the two-way stretch material.

3. A garment as claimed in claim 1, where- 85 in a bone extends lengthwise of said panel and is retained thereadjacent by means of elastic stripping forming a pocket in which the bone is received.

4. A garment of the character described 90 including material formed of elastic yarn and adapted to stretch both up and down and across, and material capable of stretching up and down but not across superimposed upon the first-named material and secured thereto along its vertical edges.

5. The garment as claimed in claim 4 95 wherein the second-named material lies at the front of the garment.

6. The garment as claimed in claim 4 100 wherein the second-named material lies at the center of the rear portion of the garment.

7. A garment of the character claimed in 105 claim 4 wherein the second-named material lies at the front of the garment and is shorter than the first-named material.

JOHN FIELD.
